APPARATUS FOR LIFTING FLUIDS

Jeddy D. Nixon, New Braunfels, Tex.

Application June 30, 1945, Serial No. 602,561

15 Claims. (Cl. 103—234)

1

This invention relates to new and useful improvements in apparatuses for lifting fluids.

The invention has more particularly to do with an improved apparatus for lifting liquids in wells, especially water wells.

One object of the invention is to provide an improved apparatus employing compressed air as a lifting medium; and being entirely automatic in its operation as well as making for high efficiency of production and low cost of both operation and maintenance.

An important object of the invention is to provide an improved liquid lifting apparatus employing a suitable compressed air supply connected with the well eduction tubing through a separate line, in which an automatic control valve is connected and which valve, also has connection with the well discharge conductor; whereby compressed air under a predetermined lifting pressure, is automatically and periodically, supplied to the eduction tubing in sufficient quantity to rapidly lift a predetermined head of liquid and which supply of compressed air is automatically shut off by the back pressure of the discharged liquid, when the latter is applied thereto, thus permitting the source of compressed air supply to rebuild the pressure to supply the next lifting period.

A further object of the invention is to provide an improved liquid lifting apparatus employing an eduction tubing and an air supply line extending down into the well externally of the tubing, together with a plug or ball having a seat above the air inlet and a relatively close sliding fit in said tubing, whereby the compressed air forces the ball to the top of the tubing and the ball in turn elevates a slug or volume of liquid accumulated in the tubing above the seated ball; the ball falling down to its seat when the supply of compressed air is shut off.

Another object of the invention is to provide an improved liquid lifting apparatus wherein the eduction tubing is allowed to free itself of compressed air after each lifting operation, whereby the tubing pressure is reduced to atmospheric pressure after each operation and the apparatus is left free to build up the pressure without interference from air left in said tubing.

Still another object of the invention is to provide means for cutting off the supply of compressed air, beyond the compressor tank, whereby a higher pressure may be built up in the compressor tank for kicking off the well, after an idle period.

A further object of the invention is to provide

2

a lifting apparatus of the character described wherein means is provided between the inlet to the tubing and the control valve, for trapping compressed air or pressure fluid in the line between said means and the inlet to the tubing, whereby a head of pressure in the line is maintained between lifting periods; and also whereby, the automatic valve is shut off from the line when fluid pressure in said valve falls below the fluid pressure in said line, thus preventing bleeding back of the compressed air from the line and speeding up the closing action of the control valve.

Another very important object of the invention is to provide a well liquid lifting apparatus whereby a predetermined sizeable load or slug of liquid may be, not only lifted at a relatively high rate of speed, but with a comparatively low expenditure of lifting fluid, thus providing a highly desirable production of liquid from a well at a very low cost, as well as producing greatly increased quantities of liquid in a given over all period of time, in comparison with apparatuses now in common use.

25 A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a diagrammatical view showing an apparatus constructed in accordance with the invention,

35 Fig. 2 is an enlarged view partly in elevation and partly in section, showing the upper end of the eduction tubing and the air supply line,

Fig. 3 is an enlarged view partly in elevation and partly in section, showing the lower end of said tubing and air supply line,

40 Fig. 4 is a transverse, vertical, sectional view of the control valve, and

Fig. 5 is an elevation of a plug which may be used instead of the ball.

This application is filed as a continuation-in-part of my co-pending application, Serial No. 539,422, filed June 9, 1944.

In the drawing, the numeral 10 designates the 50 casing of an ordinary well and 11 an eduction or discharge tubing disposed therein. The lower end of the tubing 11 is screwed into a coupling block 12 which has a vertical passage or bore 13 extending through one side thereof. The coupling block has screwed into its lower end, a nip-

ple 14 and a bull-plug strainer 15 is connected to the lower end of the nipple by a collar 16. An ordinary standing valve 17 which may be of any suitable construction is mounted in the lower end of the nipple.

An air line 18 extends down the casing 10 exteriorly of the tubing 11 and has its lower end screwed into the upper end of an inlet duct 19 in the block 12, which is connected with the bore 13 by a lateral port 20. The air line 18 which is referred to in the well industry as a "macaroni string" is attached to the tubing by clamps 21. Each clamp has a bore 22 to snugly receive the tubing and a smaller bore 23 to snugly receive the line 18. These clamps may be attached to the tubing and air line by set screws 24 as shown in Fig. 1. In order to facilitate assembling of the tubing and air lines, the sections of tubing are connected by collars 25 engaging the underside of each clamp and the sections of the line 18 are connected by collars 26 engaging the upper side of each clamp. This arrangement not only permits a ready connecting of the tubing and air line sections, but it serves to securely hold the clamps in position and to prevent their displacement. The uppermost clamp 21 rests upon a surface header 27 of suitable construction, whereby the tubing and air line are adequately supported in the well. A T 28 is screwed on to the upper end of the tubing and rests upon the upper clamp 21, thus aiding in carrying the tubing load.

The bore 13 of the coupling block 12 has a diameter less than the internal diameter of the tubing 11 and is provided with a seat 29 at its upper end to support a ball 30. This ball may be made of any suitable material, such as rubber, soft or hard plastic or metal, or a combination of the same. If the material of which the ball is composed should be too buoyant to properly sink in the column of liquid to the seat 29, it may be loaded with a suitable metal. The elevating member may take the form of a ball, plug or piston. A plug as shown at 31 in Fig. 5 may be used. This plug may be composed of soft plastic, such as synthetic rubber, and provided with washers 31' at each end connected by a bolt 30' and a nut 29'. If the plug wears, the nut may be tightened to compress and expand the plug.

In order to prevent the ball 30 from closing the end of the pipe 18', a pin 28' is inserted in the T 28 across the end of said pipe. A check valve 35' is connected in the line 18 adjacent the valve 35 arranged to close and prevent compressed air from the line 18 flowing or bleeding back into the valve 35. It is pointed out that the block 12 at the bottom of the tubing 11 is usually positioned a substantial distance below the standing level of the water in the casing 10; as an illustration 40 or 50 feet, or more. The water will also rise to approximately the same level in the tubing as in the casing, thus when the ball 30 is seated, there will be a column of water standing in the tubing above said ball.

From the foregoing, it will be seen that because of the column of water or liquid standing above the tubing inlet 20, a liquid seal thereacross will be provided, although the port remains open for the entrance of compressed air to the tubing. This seal coating with the check valve 35' provides means for trapping a head of compressed air in the line when the lifting operation is completed or nearly so. The height of the column of liquid will of course control the pressure of

the trapped air. A column of liquid standing in the usual water well tubing, approximately 40 feet above the inlet 20, will hold the trapped air under substantially 20 pounds pressure per sq. in. By the time the liquid load being lifted leaves the tubing, the pressure of the compressed air entering the tubing will be greatly reduced and therefore, the head of liquid standing in the casing 10 will flow into the tubing through the standing valve 17 and rise in said tubing, thus trapping air in the line 18. Liquid will immediately begin to enter the tubing from the formation and raise the column of liquid in the tubing to its normal or working level.

The upper end of the valve 35 is connected by a back pressure pipe 36, with a T 37 connected in the discharge pipe 34, as is shown in Fig. 1. An elbow 38 is connected with the lower end of the valve 35 and also with a cut-off valve 40, which in turn, is connected with one end of the compressor tank 39 of an air compressor A. Any suitable air compressor may be used. A satisfactory type is shown generally in Fig. 1 and includes the tank 39 with an air compressor 41 and a small gasoline engine 42, mounted thereon. The air compressor is driven by the engine in the usual manner. The tank also carries a pressure gage 42'. When the type of compressor shown in Fig. 1 is used, the engine is operated continuously, except when the well is shut down; however, a type employing starting and stopping means (not shown) could be used, such types being now in common use.

The control valve 35, which will be herein-after described in detail, is constructed so that when the pressure in the tank 39 reaches the predetermined degree which for the purpose of illustration, may be 100 lbs. to the square inch, the valve opens and supplies compressed air to the line 18 by way of the lateral 18'. The compressed air after filling the pipe 18 flows through the duct 19 and port 20 into the bore 13. In the meantime, the standing valve 17 has opened and permitted an accumulation of water to enter through the nipple 14 and bore 13 and rise in the tubing, as hereinbefore described. The ball will temporarily be unseated to permit the water to rise up to its working level in the tubing 11, after which the ball will seat. When compressed air is admitted to the bore 13, it will force the ball 30 upwardly thus elevating the water trapped thereabove and carry it up the tubing 11 into the T 28 in a slug. The ball 30 will be arrested by the plug 33, and will be retained in the T 28 by the pin 28', while the water is being discharged through the pipe 34. It is obvious that the slug of water being substantially solid, channeling of the air therethrough will not occur.

A portion of the water, which is discharged into the pipe 34, will flow into the back pressure pipe 36, act upon the valve 35, and in conjunction with the check valve 35, shut off the supply of compressed air to the line 18. When the compressed air is shut off, the pressure in the tubing 11 will be sufficiently reduced to permit the ball 30 to fall by gravity and come to rest on the seat 29.

While the particular construction of the valve 35 is subject to variation, the valve shown in Fig. 70 4 has been found to give very satisfactory results. This valve includes an upright tubular casing 45 provided with a bore 46 at its lower end, an intermediate enlarged bore 47 and an upper bore 48. The lower end of the bore 46 is internally 75 screw-threaded to receive the screw-threaded

shank 49 of a plug 50 provided with a nipple 51 on its lower end which is screw-threaded and adapted to be screwed into the elbow 38. A packing ring 52 is interposed between the plug and the lower end of the casing 45. A header 53 is provided with a reduced screw-threaded shank 54 which is screwed into a socket 55 in the upper end of the casing. A packing ring 56 is interposed between the header and the upper end of the casing. The header has an enlarged annular cup 57 at its upper end which is externally threaded to receive the internally screw-threaded flange 58 of a cap 59 which has a central screw-threaded boss 60 on its upper side.

A flexible diaphragm 61 is clamped around its marginal edge between the cup 57 and the cap 59 and a metal follower disk 62 may be suitably fastened to the bottom of the diaphragm or may be held in contact therewith by a coiled spring 65. A guide collar 64 depends from the center of the disk. The shank 54 of the header is provided with an axial well 64 in which the coiled spring is supported. The upper end of this spring surrounds the boss 63. A reduced guide sleeve 66 is made integral with the lower end of the shank 54 and has a reduced bore 67 which terminates in an enlarged bore 68 at the lower end of the sleeve which in turn, has a beveled seat 69 at its lower end.

An upright valve stem 70 extends through the elements 69, 68, 67, 66 and into the collar 63 but terminates short of the top of the bore of said collar. The valve stem extends upwardly from an inclined valve shoulder 71 formed on the upper end of a cylindrical valve body 72 having spaced annular collars or pistons 73 made integral therewith and preferably made integral with the valve body. An axial valve pin 75 depends from the lower piston and has its lower end beveled at 76 to engage in a valve seat 77 formed at the upper end of an axial duct 78 disposed vertically in the plug 50. The pistons have a snug sliding fit in the bore 46 and are made of sufficient height to form guides for the valve body 72 and to maintain the same in an upright sliding position. A plurality of vertical ports 79 are provided in the collars so as to permit the compressed air to flow therethrough. The pin 75 is held on the seat 77 by a coiled spring 80 surrounding the sleeve 66 and the valve body 72 and confined between the upper portion 73 and the lower end of the shank 54.

It will be observed that the spring 65 is under compression and acts to support the diaphragm in its normal horizontal position; while the spring 80 is also under compression and acts to force the pin 75 onto the seat 77. The valve stem 70 having a loose sliding fit in the collar 63, it is obvious that the diaphragm is movable independently of said stem. An internally screw-threaded outlet boss 81 extending from the bore 47 receives the lateral 18', whereby compressed air supplied by the compressor 39 is delivered to the line 18. It will also be observed that the reduced bore 67 has an internal diameter which is greater than the external diameter of the valve stem 70, whereby compressed air may pass upwardly along the stem and escape into the header 53 which later is provided with vent ports 82.

When the predetermined air pressure, as for illustration 100 lbs. per sq. in., has been built up in the compressor tank 39, the compression of the spring 80 will be overcome because the air will act against the lower end of the pin 75, thus raising its inclined surface from the seat 77, whereby

compressed air will be discharged into the bore 46 and pass upwardly through the ports 79 and to the lateral 18'.

Owing to the area of the underside of the lower collar 73, which is exposed to the compressed air, the body 72 will be rapidly, in fact, almost instantaneously, lifted to cause the shoulder 71 to engage the seat 69, upon sufficient air entering the bore 46. This force will raise and seat the body 72 with a snap or quick action. Because of the space in the collar 63, above the stem 70, the shoulder 71 will engage the seat 69 without displacing the diaphragm 61. The sealing of the valve body 72 will prevent escape of air through the ports 82.

When the water or liquid is being discharged through the pipe 34, a back pressure will be built up against the top of the diaphragm 61, through the pipe 36, which is comparatively small with relation to the pipe 34. It is apparent that by the time the ball 30 enters the T 28, the load or slug of liquid will have been discharged and the pressure of the compressed air flowing into the lateral 18', as well as the air pressure in the tank 39, will be greatly reduced.

The upward movement of the body 72 compresses the spring 80, so that when the pressure in the valve casing 45 drops to a predetermined point, the back pressure acting upon the diaphragm will start the same downwardly, thus breaking the contact or seal between the shoulder 71 and seat 69, and thereby cracking the seal and releasing the air from the bore 47 to the ports 82. This movement, coupled with the expansive force of the compressed spring 80 will quickly, and almost instantaneously, move the valve body downwardly and engage the pin 75 with the seat 77 to close the valve with a snap action. The snap seating of the shoulder 71 and the pin 75 is very advantageous because the sudden impact keeps the seating surfaces clean as well as maintaining tight seats. When the diaphragm is depressed, the spring 65 is compressed so that, as the back pressure drops, the spring raises said diaphragm to its horizontal position.

The time elapse between the opening and closing of the valve 35 is, in most installations, very short, even less than a minute. The rate of travel of the ball 30 up the tubing is controlled by the clearance between the collar 73 and the wall of the bore 46, which clearance is, of course, subject to variation. This short operation period not only makes for rapid lifting of the load of liquid, but involves rapid action of all elements, as well as an economical expenditure of compressed air. The time lag between lifting cycles, during which lag the valve 35 remains closed, depends upon the time required for the compressor A to build up the reduced pressure in the tank 39. Thus, if the pressure drop is 20 lbs. to the square inch, the time required to rebuild the pressure is less than if the drop was 30 lbs. per sq. in. Where the starting pressure is 100 lbs. per sq. in., satisfactory operation has been carried out with a drop of 20 lbs. per sq. in.

The check valve 35 is important because it traps air under pressure in the lateral 18' and line 18, thus reducing the amount of air which must be supplied to carry out the next lifting cycle. It is pointed out that when the ball 30 reaches the top of the tubing the pressure of the air in the line 18 and lateral 18', before the valve body 72 moves downwardly, may be greater than the air pressure in the control valve 35, thus

closing the check valve 35' and trapping air under pressure in the line 18 and lateral 18'. However, it may occur that the shoulder 71 will be unseated and air released from the valve 35 before the check valve 35' closes. In either event the check valve will close and air under pressure will be trapped and not bled from the line.

It is obvious that when a well remains idle for many hours or days, the liquid will rise in the tubing to a height greater than the working level to which it rises during the lifting cycles, therefore, when it is desired to again start lifting liquid, it will be necessary to "kick off" the well and this will require a higher pressure than the working pressure built up in the tank 39 during lifting cycles. For this purpose, the cut-off valve 40 is provided. By closing this valve the required kick-off pressure may be accumulated in the tank, after which the valve 40 may be opened and regular operation automatically started. It is to be understood that the term "ball" used generically in the specification and claims, is intended to cover a ball, plug or piston and the like. Also, the term "compressed air" as used generically in the specification and claims, is intended to cover any pressure fluid suitable for the purpose. Further, the apparatus may be used in a well having only a surface casing. It is to be understood that the ball 30 and the plug 33 may be omitted, so that the slug of liquid will be lifted directly by the compressed air.

It is to be understood that while a "pop off" or working pressure of 100 pounds per sq. in. may be built up in the storage tank 39, the compressed air delivered to the pipes 18' and 18 may have a considerably lower pressure, as for instance 60 pounds per sq. in., or even lower. The amount of pressure which can be built up or maintained in the pipes 18' and 18 depends upon the height of the head of liquid standing in the tubing above the inlet 20, because when the pressure of the air exceeds the hydrostatic weight of this liquid head, such head will start moving up the tubing. Thus, while a pressure of 100 pounds per sq. in. may be carried in the compressor tank 39, only a pressure of 60 pounds per sq. in. may be required to lift the liquid load.

When a well remains idle for several hours or days, the liquid in the tubing will rise to a higher level than it will when the well is being operated at regular intervals; thus, there will be a maximum or static level and a working level therebelow. It is obvious that a greater pressure will be required to lift the liquid when it is at the maximum level because of the increased hydrostatic load. Thus, where a pressure of 60 pounds per sq. in. may be adequate to operate the well from the working level, a pressure of 80 pounds per sq. in. may be required to lift the liquid load when the fluid stands at the maximum level. However, as the operation of the well progresses, the level will drop at successive lifting cycles and the pressure requirements will likewise drop until the working level and working pressure are reached. Thus it is necessary to build up a reserve pressure in the tank 39.

Owing to the relatively large area of the diaphragm 61 and the comparatively lesser areas of the surfaces being acted upon by the compressed air, when the valve 35 is open, such diaphragm is very sensitive and will respond or yield to low pressures. For instance, where the pressure of the air being supplied to the tubing may be approximately 60 pounds per sq. in., the diaphragm will yield to a pressure of less than 10

pounds per sq. in. Of course, as soon as the valve member 12 moves its shoulder 71 downwardly from the seat 69, the pressure in the bore 46 will be released and the valve pin 75 will be snapped to its seat 77. The check valve 35' will close substantially simultaneously with the release of pressure in the valve 35. This arrangement makes for a quick trapping of the compressed air in the pipes 18' and 18 and aids in limiting the pressure drop in said pipes.

It is pointed out that by the time the ball 30 falls to its seat 29, or soon thereafter, all of the compressed air utilized in lifting said ball and the slug of liquid will have escaped into pipe 34 and consequently the pressure in the tubing 11, will reduce to atmospheric. This is important as no compressed air pressure is trapped in the tubing and it is only necessary to build up pressure in the string 18 to elevate the slug of liquid.

It will be noted that the string 18 is considerably less in diameter than the eduction tubing 11. This is important because it makes for conservation in the expenditure of compressed air. Where eduction tubing is 2 inches, internal diameter, the pipe 18 for many installations need not be over $\frac{1}{2}$ inch internal diameter. A small pipe is more readily filled with compressed air between the inlet 20 and the control valve 35 and consequently the loss of compressed air after each lifting operation is greatly reduced. Further, once the valve 35 is opened, the supply of compressed air quickly builds up in the small string 18, particularly if air under pressure has been trapped therein between the check valve 35' and the liquid column in the tubing. Thus, the lag between the opening of the compressed air supply and the initial movement of the slug of liquid is reduced over where large air supply pipes are used.

It is preferable to make the seat 29 so that it will not close off the passage when the ball 30 rests thereon, which permits liquid to freely flow upwardly when the ball is seated or arrested.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A liquid lifting apparatus including, an eduction tubing adapted to be disposed in a well with its lower end below the liquid level in said well and having an inlet valve below said liquid level, means for supplying compressed air to the tubing above the inlet valve and below the liquid level in the tubing to cut off a slug of liquid above the point of admission and elevate said plug to the top of the tubing and discharge it therefrom, and control means connected in said pressure fluid supply connected with the top of the tubing and having pressure-responsive means for cutting off the supply of pressure fluid responsive to a low pressure, and means adjacent the control means for trapping pressure fluid between the supply means and the point of admission to the tubing.

2. A liquid lifting apparatus including, an eduction tubing adapted to be disposed in a well with its lower end below the liquid level in said well and having an inlet valve below said liquid level, a pressure fluid supply line of greatly less diameter than the diameter of the tubing connected directly into the tubing above the inlet

valve and below the said liquid level for supplying pressure fluid to lift a slug of liquid, whereby said line is quickly filled with pressure fluid and the supply of pressure fluid is conserved, means at the top of the well responsive to a reduced fluid pressure for shutting off the supply of pressure fluid to said line when the slug reaches the top of the tubing, and means for trapping pressure fluid in the line after the supply thereto is cut off.

3. A liquid lifting apparatus including, an eduction tubing adapted to be disposed in a well with its lower end below the liquid level in said well and having an inlet valve below said liquid level, means for supplying compressed air to the tubing above the inlet valve and below the liquid level therein, a control valve connected with supply means and having a fluid pressure-responsive cut off below its point of connection to said supply means and a vent above said connection, and a back pressure valve in said supply means adjacent said control valve adapted to shut off back flow of pressure fluid in said supply means when the vent of said control valve is open to trap pressure between the tubing and itself.

4. A liquid lifting apparatus as set forth in claim 3 with means responsive to pressure differentials for periodically shutting off and subsequently opening the supply of compressed air.

5. A liquid lifting apparatus including, an eduction tubing adapted to be disposed in a well with its lower end below the liquid level in said well and having an inlet valve below said liquid level, means for supplying compressed air to the tubing above the inlet valve and below the liquid level in the well to lift liquid and discharge the same from the tubing including a source for building up and supplying compressed air at a predetermined pressure, control means adapted to open and supply compressed air when a predetermined pressure is built up at said source and connected with the discharge end of the tubing and exposed to the discharge fluid for operation thereby to shut off the supply of compressed air to the tubing, and a movable member separate from the inlet valve seated in the tubing between the compressed air inlet and the liquid level therein adapted to be elevated by the compressed air to lift the liquid accumulated thereabove and adapted to fall down the tubing to its seat.

6. A liquid lifting apparatus including, an eduction tubing adapted to be disposed in a well with its lower end below the liquid level in said well and having an inlet valve below said liquid level, means for supplying compressed air to the tubing above the inlet valve and below the liquid level in the well to lift liquid and discharge the same from the tubing including a source of compressed air supply for supplying said air at a predetermined pressure and control means connected in the supply means and connected with the discharge end of the tubing adapted to open when said predetermined pressure is built up and exposed to the discharged fluid for operation thereby to shut off the supply of compressed air to the tubing, and a movable member separate from the inlet valve seated in the tubing between the air inlet and the liquid level therein adapted to be elevated by the compressed air to lift the liquid accumulated thereabove and adapted to fall down the tubing to its seat.

7. A liquid lifting apparatus including, an eduction tubing adapted to be disposed in a well with its lower end below the liquid level in said well and having an inlet valve at its lower end,

10
5 a discharge pipe leading from the upper end of the tubing, an air supply line extending longitudinally of the tubing in the well and connected with the tubing below the liquid level in the well, means for supplying compressed air to the air line, a control valve connected with the air line and having means for supplying compressed air to the air line when opened, means for conducting a portion of the fluid discharged from the well to the valve to close the same, and a movable member separate from the inlet valve seated in the tubing between the air inlet and the liquid level therein adapted to be elevated by the compressed air to lift the liquid accumulated thereabove and to return down the tubing to its seat.

20
8. A lifting apparatus including, an eduction tubing adapted to be disposed in a well with its lower end below the liquid level therein and having an inlet valve below said liquid level for accumulating a head of liquid in said tubing, means for supplying compressed air to the tubing and to said head of liquid to lift and discharge said liquid from the tubing, control means connected in the compressed air supply means and exposed to the pressure of the discharged liquid for automatically supplying and cutting off the compressed air, said control means being responsive to a pressure lower than the lifting pressure applied to the head of liquid to shut off the supply of compressed air, and means co-acting with the control means and separate therefrom for trapping a volume of compressed air between said control means and the inlet to the tubing.

35
9. A liquid lifting apparatus including, an eduction tubing adapted to be disposed in a well having liquid standing therein with its lower end below the liquid level in said well, a liquid inlet at the lower end of the tubing, a pressure-fluid line extending substantially parallel of the tubing and having its lower end connected with the tubing normally open for discharging pressure fluid into the tubing below the liquid level in said well and above the liquid inlet to lift liquid in said tubing, means above ground for supplying a pressure fluid to said line, means connected to said line and with said supply means responsive to pressure differentials for automatically starting and shutting off the supply of pressure fluid to said line, and means for trapping a head of pressure fluid in said line between its inlet to the tubing and said automatic means.

50
10. A liquid lifting apparatus including, an eduction tube adapted to be disposed in a well with its lower end below the liquid level in said well and having an inlet valve below said liquid level, means for supplying compressed air to the tubing above the inlet valve and below the liquid level in the well to lift liquid and discharge the same from the tubing including a source for building up and supplying compressed air at a predetermined pressure, control means adapted to open and supply compressed air when a predetermined pressure is built up at said source and connected with the discharge end of the tubing and exposed to the discharged fluid for operation thereby to shut off the supply of compressed air to the tubing, and means separate from the control means for trapping a head of compressed air in said supply means between the control means and the tubing when the load of liquid reaches the top of the tubing.

60
11. A liquid lifting apparatus including, an eduction tubing adapted to be disposed in a well with its lower end below the liquid level

11

in said well and having an inlet valve at its lower end, a discharge pipe leading from the upper end of the tubing, an air supply line extending substantially parallel of the tubing in the well and connected with the tubing below the liquid level in the well, means for supplying compressed air to the air line, a control valve connected with the air line and having means for supplying compressed air to the air line when opened, and means connected in said supply line 10 for trapping compressed air therein.

12. A liquid lifting apparatus including, an eduction tubing adapted to be disposed in a well with its lower end below the liquid level in said well and having an inlet valve below said liquid level, means for supplying compressed air to the tubing above the inlet valve and below the liquid level in the well to lift liquid and discharge the same from the tubing including a source of compressed air supply for supplying said air at a predetermined pressure and control means connected in the supply means and connected with the discharge end of the tubing adapted to open when said predetermined pressure is built up and exposed to the discharged fluid for operation thereby to shut off the supply of compressed air to the tubing, and means connected in the air supply for trapping compressed air therein when the said movable member reaches the top of the tubing.

13. A liquid lifting apparatus including, an eduction tubing adapted to be disposed in a well with its lower end below the liquid level in said well and having an inlet valve at the lower end, a discharge pipe leading from the upper end of the tubing, an air supply line extending substantially parallel of the tubing in the well and connected with the tubing below the liquid level in the well, means for supplying compressed air to the air line, a control valve connected with the air line for controlling the supply of compressed air to the air line when opened, and a check valve in the air line for trapping compressed air therein when the control valve is closed.

14. A well liquid lifting apparatus including, an eduction tubing adapted to be disposed in a well having liquid standing therein, a liquid inlet at the lower end of the tubing, an air line extending substantially parallel of the tubing

5

having a normally open inlet to the tubing at its lower end below the liquid level of the well for supplying compressed air to the tubing to elevate liquid to the top thereof, the liquid inlet admitting liquid to the tubing, whereby liquid rises in the tubing above the open inlet of the air line, means for supplying compressed air to the air line, control means connected with said compressed air supply means and said line and also connected with the upper end of the tubing for automatically starting and shutting off the supply of compressed air to the line, and means separate from the control means connected in the line adjacent the control means and co-acting with the liquid accumulated in the tubing for trapping compressed air in said line between the control means and the open inlet to the tubing.

15. A well liquid lifting apparatus including an eduction tubing having a liquid inlet valve connected to its lower end for admitting liquid directly from a well source to the tubing and a seat in the tubing above the inlet valve, said tubing being continuous from the well inlet valve to the seat and above said seat, said tubing having a compressed air inlet therein between the valve and the seat, means separate from the tubing for conducting compressed air downwardly of the tubing directly to the air inlet of said tubing, and a liquid lifting ball normally resting upon said seat and adapted to be lifted by the compressed air to the top of the tubing to elevate liquid admitted to the tubing.
